MAGNETIC TAPE CARTRIDGE FOR VIDEO-TAPE RECORDER

Yoshiji Koni, Nara, Japan, assignor to Matsushita
Electric Industrial Co., Ltd., Osaka, Japan

Filed Aug. 8, 1972, Ser. No. 279,135

Term of patent 14 years

Int. Cl. D14—01

U.S. Cl. D26—14 B

FIG. 1

FIG. 2

FIG. 1 is a top, front left hand, perspective view of a magnetic tape cartridge for a video-tape recorder showing my new design; and

FIG. 2 is a bottom, rear, left hand, perspective view thereof.

I claim:

The ornamental design for a magnetic tape cartridge for video-tape recorder, as shown.
